GOLF JACKET

Lewis L. Russfield, Boston, Mass.

Application April 15, 1950, Serial No. 9,246

Term of patent 3½ years

(Cl. D3—4)

To all whom it may concern:

Be it known that I, Lewis L. Russfield, a citizen of the United States of America, residing in Boston, county of Suffolk, and State of Massachusetts, have invented a new, original, and ornamental Design for a Golf Jacket, of which the following is a specification, reference being had to the accompanying drawing, forming part thereof.

Fig. 1 is a front view of a golf jacket, showing my new design.

Fig. 2 is a rear view thereof.

Fig. 3 is a fragmentary view illustrating the zippered portions of the collar and pocket in open positions.

I claim:

The ornamental design for a golf jacket, substantially as shown.

LEWIS L. RUSSFIELD.
